(57) **CLAIM**

The ornamental design for a foldable battery dock, as shown and described.

DESCRIPTION

FIG. 1 is a top front right perspective view of a Foldable Battery Dock showing my design;

FIG. 2 is a bottom rear right perspective view thereof;

FIG. 3 is a top front right perspective view thereof with the foldable panel in a fold-up position;

FIG. 4 is a top rear left perspective view thereof with the foldable panel in a fold-up position;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.
